UNITED STATES PATENT OFFICE.

THOMAS J. STEARNS, OF BOSTON, MASSACHUSETTS, ASSIGNOR TO THE
ROXBURY CARPET COMPANY, OF SAME PLACE.

DESIGN FOR A CARPET.

SPECIFICATION forming part of Design No. 12,587, dated November 29, 1881.

Application filed October 21, 1881. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed of the free-hand floral and foliage designs or bouquets of different sizes alternating with each other across the figure, and the ground ornamented by a large variety of minor designs, composed of a fan-shape figure, a circle divided into quarters and 15 ornamented with parallel lines and with scrolls, a circular figure composed of concentric rings,

and a number of smaller figures not easily described, the whole forming a sort of chintz-work of conventional forms thickly covering the ground between free-hand and foliage designs.

I claim—

The design for a carpet, substantially as shown and described.

In testimony whereof I have signed my name 25 to this specification in the presence of two subscribing witnesses.

THOMAS J. STEARNS.
